UNITED STATES PATENT OFFICE

MANUEL G. GUERRA, OF LAREDO, TEXAS

BOLL WEEVIL EXTERMINATING MACHINE

Application filed March 4, 1930. Serial No. 433,108.

This invention relates to an improvement in boll weevil exterminating machines.

The object of the invention is to furnish a means of protection against boll weevils or other insects which tend to destroy the cotton, particularly during its budding period, and in the case of an epidemic already having set in, this invention will prevent its spreading.

10 Among many advantages of this machine, the following may be mentioned as the principal ones:

First: to gather the fallen cotton flower which already has been damaged and which 15 may contain the insect, thus preventing the spreading of an epidemic;

Second: to gather the mature boll weevils by means of oil pans or the like; and

Third: to apply a poisonous solution of a 20 suitable insecticide or the like effectively and directly to the plant.

In the accompanying drawings:

Fig. 1 is a horizontal sectional view 25 through the complete machine;

Fig. 2 is a rear elevation of the same;

Fig. 3 is a transverse sectional view there- 30 through;

Fig. 4 is a longitudinal sectional view taken at a different point from Fig. 1;

Fig. 5 is a top plan view of the machine;

Fig. 6 is a perspective view of the receiving box; and

Fig. 7 is a similar view of one of the oil 35 pans.

The invention is adapted to be carried or mounted on any suitable or desired character of vehicle, either motor propelled or otherwise, and for the purpose of illustration is herein shown as applied to a horse-drawn

40 vehicle, in which the frame is designated generally by the numeral 1 and is supported on traction wheels 2. The forward end of the frame has attached thereto the usual tongue 3 and whiffle trees 4 for the draft. An operator's seat 5 may be supported at the rear of the frame, and additional seats, such as a driver's seat or the like, may be provided where found suitable and desirable.

Mounted on opposite sides of the frame 1 45 are box-like casings 6, each of which has a

depending portion 7 at the rear end thereof for a purpose hereinafter to be described.

An elbow 8 is attached to each of the box-like casings 6 near the top thereof, with its open end turned downward, and has secured thereto a flexible tube 9, which in turn has attached thereto tubes 10 and 11 telescopically fitted together so that the lowermost tube 11 may be raised or lowered, and this collector tube 11 is normally held in an elevated position by means of springs 12. A stirrup 13 is attached to the inner side of each of the collector tubes 11 to receive the foot of the operator for raising and lowering the collector tubes as the machine is propelled or moved along the row.

Communicating with each of the elbows 8 and extending horizontally through each of the box-like casings 6 is a conduit 14 which extends to the suction side of a fan 15 mounted in a fan casing 16 and on the shaft 17, which shaft is driven by means of a belt 18 from a head shaft 19, which is in turn driven by belts 20 from a motor 21 as a source of power for the fan within each of the box-like casings 16.

Extending rearwardly from each fan casing 16 is a discharge tube 22, which extends through a wall 23 in the box-like casing 6 and discharges the collected flowers into the lower portion 7 of this casing. A receiving box 24 is disposed within this lower portion 7 and beneath the discharge end of the tube 22 to receive the collected flowers. This receiving box is slidably mounted in the lower portion 7 of the casing so as to be removed for destruction of the collected flowers and insects.

The wall 23 in the casing 6 may be perforated as at 25 to allow any fumes to escape from the casing through a vent 26 in the top thereof.

Telescopically connected with and extending downwardly from each of the fan casings is a discharge elbow 27, the elbows on opposite sides of the machine being turned toward each other so as to be disposed on opposite sides of the plants or flowers as the machine passes along the row.

As a means of regulating and controlling the discharge from the fan casing 16, a gate

or vane 28 is disposed therein and is preferably perforated or reticulated so as to allow a constant draft of air through the elbow 27, while yet not allowing the collected flowers to pass therethrough, the latter being blown out through the tube 22. This vane or gate 28 may be controlled by a suitable lever 29, which extends to a point within convenient reach of the operator. Guides 30 are disposed in opposed relation at the front of the frame 1 of the machine to direct the flowers or plants between the elbows 27 and between the lower portions 7 of the box-like casings 6. These guides 30 are provided with vertical slots 31 therein for receiving and through which the elbows 27 extend, and are adjustably mounted for different elevations.

Disposed in each of the elbows 27 is a fan-shaped spray nozzle 32 adapted to spray the fluid insecticide onto the flowers or plants as the machine passes along a row, which fluid is supplied through a pipe 33 from a tank 34 mounted upon the box-like casing 6. The supply of insecticide is controlled by means of a valve 35 regulated by a control lever 36 which also extends to a point within convenient reach of the operator.

Mounted on the inner sides of the lower sections 7 of the casings 6 are oil pans 37 which contain a suitable poison or insecticide to receive and destroy the insects. These pans 37 are open at the top but suitable screens 38 extend over the same to prevent the flowers from falling into the pans. Guides 39 are secured at the forward sides of the lower portions 7 to direct the flowers or plants between the oil pans 37.

The machine is drawn along the row and so as to straddle the row of cotton stalks or plants, either by self-propelled mechanism or otherwise, and the cotton stalks are directed by the guides 30 first between the elbows 27, where they are sprayed with an insecticide through the nozzles 32 and the air discharged from the fans through said elbows. Further movement of the machine causes the stalks to be guided by the guides 39 between the oil pans 37 and at least some of the boll weevils or insects fall from the plants into the pans through the screens 38.

The flowers or portions of the cotton or stalks that have become dislodged and have fallen to the ground are collected by the collectors 11 and the suction created therein by the fans and drawn through the fans and the tubes 22 and discharged into the receptacles 24, from where they may be removed for destruction either by burning or otherwise.

The force of the fans also acts through the baffles 28 and the elbows 27 to enhance the spraying action of the insecticide from the nozzles 32, which insecticide is supplied from the tanks 34, the supply being regulated by the valves 35 and levers 36, from within convenient reach of the operator.

I claim:

1. In a machine of the character described, the combination of a collection receptacle, a suction device for discharging into said receptacle, collecting tubes communicating with the suction of said suction device, said collection tubes being telescopically and slidably connected together, resilient means normally tending to move the lower ends of the collecting tubes upwardly, and straps connected therewith for manually moving the tubes downwardly against the tension of the resilient means. 70

2. In a machine of the character described, the combination of a collection receptacle, a suction device for discharging into said receptacle, collecting tubes communicating with the suction of said suction device, said collection tubes being telescopically and slidably connected together, means for normally tending to move the collection tubes together, and means for sliding one of the tubes outwardly of the other. 85

3. In a machine of the character described, the combination of a casing having an extended lower portion, a receptacle removably received within said lower portion, a partition provided within said casing and separating the lower and upper portions thereof, a fan casing disposed within the main casing and having a discharge tube extending through the partition for discharging into the receptacle, and a collecting device communicating with the fan casing. 90

4. In a machine of the character described, the combination of a casing having an extended lower portion, a receptacle removably received within said lower portion, a partition provided within said casing and separating the lower and upper portions thereof, a fan casing disposed within the main casing and having a discharge tube extending through the partition for discharging into the receptacle, a collecting device communicating with the fan casing, a separate discharge tube extending downwardly from and communicating with the fan casing, an insecticide spray nozzle disposed within the outlet of the last-mentioned tube, and a source of supply communicating with said nozzle. 100

5. In a machine of the character described, the combination of a frame, enclosed casings disposed on opposite sides of said frame and in spaced relation to straddle a row of cotton stalks and the like, each of said casings having a depending lower portion, a partition disposed in and separating the lower and upper portions of said casing, a receptacle removably mounted in the lower portion, a fan casing mounted in the upper portion and having a discharge tube extending through the partition to discharge into the receptacle, discharge elbows extending downwardly from the fan casings and discharging in opposed relation, means for adjusting the point of dis- 110

charge of said elbows, an insecticide spray nozzle disposed within the discharge end of each elbow, and a source of supply communicating with said nozzle.

6. In a machine of the character described, the combination of a frame, enclosed casings disposed on opposite sides of said frame and in spaced relation to straddle a row of cotton stalks and the like, each of said casings having a depending lower portion, a partition disposed in and separating the lower and upper portions of said casing, a receptacle removably mounted in the lower portion, a fan casing mounted in the upper portion and having a discharge tube extending through the partition to discharge into the receptacle, discharge elbows extending downwardly from the fan casings and discharging in opposed relation, means for adjusting the point of discharge of said elbows, an insecticide spray nozzle disposed within the discharge end of each elbow, a source of supply communicating with said nozzle, a conduit communicating with the suction side of each fan casing, and a collecting device communicating with each conduit and having tubular members telescopically connected together, means normally tending to move said members together, and means for moving one of the members downwardly of the other.

7. In a machine of the character described, the combination of a wheeled frame, suction mechanism mounted thereon, and one or more tubular gathering units communicating with the suction mechanism, and having telescoping sections, resilient means normally tending to move the gathering end sections of said sections upward, and stirrups connected with said last-mentioned sections for manually moving the same downward.

8. In a machine of the character described, the combination of a wheeled frame, a box-like casing mounted thereon, and having an enclosed upper portion and an extended lower portion, a perforated partition separating said upper and lower portions to permit fumes to pass off from the lower portion, suction mechanism connected with the casing, and means for ventilating the upper portion of the casing.

9. In a machine of the character described, the combination of a wheeled frame, a box-like casing mounted thereon, and having an enclosed upper portion and an extended lower portion to catch material, a perforated partition separating said upper and lower portions and permitting fumes to pass through the perforations from the lower to the upper portions, means for ventilating the upper portion, and suction mechanism mounted in the upper portion and having a discharge nozzle extending through the partition.

In testimony whereof I affix my signature.
MANUEL G. GUERRA.
